UNITED STATES PATENT OFFICE.

MORRIS J. HOFFMAN, OF CHICAGO, ILLINOIS.

COUPON-TICKET-PRINTING MACHINE.

1,371,893.

Specification of Letters Patent. Patented Mar. 15, 1921.

Application filed March 24, 1920. Serial No. 368,252.

To all whom it may concern:

Be it known that I, MORRIS J. HOFFMAN, a citizen of the United States, and a resident of Chicago, Cook county, and State of Illinois, have invented certain new and useful Improvements in Coupon-Ticket-Printing Machines, of which the following is declared to be a full, clear, and exact description.

This invention relates to coupon ticket printing machines, and its principal object is to increase the efficiency of machines of this class and to otherwise improve on the construction thereof. This invention has particular reference to coupon ticket printing machines which are employed for printing information upon detachable coupons that form part of a ticket, such as are commonly employed in many establishments to keep a record of the workmen's wages. It is well known that in many establishments a coupon ticket accompanies the article, or a lot of articles to be constructed, which ticket contains a number of detachable coupons, one for each workman who performs any work upon the article. These tickets are numbered consecutively, and the coupons of the tickets are numbered to correspond with the number of the ticket itself, and the amounts to be paid to the workmen and the number of articles in the lot accompanying the ticket, are printed upon the several coupons. These coupons are often arranged along each side of the ticket and the present machine has been especially designed to print the desired data along the two rows of coupons, although it may be constructed to print along one row only if desired.

The present invention is in the nature of an improvement on the coupon ticket printing machine shown and described in Letters Patent No. 1,251,887, issued to me on January 1, 1918, to which reference is herein made.

The invention consists in the several novel features of construction, arrangement and combination of parts hereinafter fully set forth and claimed.

The invention is clearly illustrated in the drawings accompanying this specification, in which Figure 1 is a plan of a coupon

ticket printing machine embodying the present invention. Fig. 2 is a plan, with the platen, certain covers, part of the ink ribbon, and the majority of the type-bars removed to show parts that would be otherwise hidden from view. Fig. 3 is an end elevation looking in the direction of the arrow 3 in Fig. 1. Fig. 4 is a vertical cross section taken on the line 4—4 of Fig. 1. Fig. 5 is an end elevation looking in the direction of the arrow 3 in Fig. 1, but showing the platen in its raised position. Fig. 6 is a vertical cross section taken on the line 6—6 of Fig. 1. Fig. 7 is a detail skeleton view of a typesetting bar, shaft, pinions and type-bars. Fig. 8 is a detail, vertical, longitudinal section taken on line 8—8 of Figs. 2 and 6. Fig. 9 is a side elevation of a fragment of a type-bar having removable type. Fig. 10 is a detail, vertical section taken on line 10—10 of Fig. 9 and showing in addition certain type-bar supporting plates. Fig. 11 is a detail section taken on line 11 of Fig. 9 and showing said plates. Fig. 12 is a side view, and Fig. 13 an end view of one of the removable type. Fig. 14 is a detail, vertical cross section through a type-bar having fixed type and its supporting plates. Fig. 15 is a detail section taken on line 15—15 of Fig. 1, and Fig. 16 is a side elevation of a fragment of a certain type-bar.

Referring to said drawings, the reference numeral 20 designates the main frame, which may be substantially rectangular in form and provided with legs 21 for supporting it on a table, bench or other object. In said frame 20 are fixedly supported two lengthwise-extending bars 22 between which extend a number of thin, flat, type-bar supporting plates 23 which are formed with shouldered portions 24 (see Fig. 6) that rest on the tops of the bars 22. The plates 23 are clamped between the bars 22 by bolts 25 or threaded rods 25 which extend through said bars 22 and have nuts upon their threaded ends bearing against the bars 22. Said plates 23 are spaced apart and held in spaced relation by washers 26, through which extend bolts or threaded rods 27 that have nuts 28 threaded upon their ends which

clamp the plates 23 and washers 26 together to make a rigid and substantial frame for supporting and guiding the type-bars, as will be hereinafter set forth. The threaded rods 27 may extend through end plates 23^a which are also clamped between the bars 22, and the entire type-bar supporting frame, comprising the bars 22, plates 23 and bolts or rods 25, 27 may be secured to the ends 10 20^a of the frame 20 by screws, or otherwise, as is found convenient.

Slidingly supported upon the plates 23 are the type-bars 29, 30 and 31 which are arranged in groups, one group being shown 15 in Fig. 2. The other type-bars have been removed to show the construction beneath. The type-bars 29 bear permanent type characters, preferably numerals running from 0 to 9; and for convenience, four type-bars 29 20 are shown in a group which will permit of printing any number to and including the thousands column. The type-bars 30 may contain characters indicating grades or the combination of prices to be paid for the 25 work done, and the type-bars 31 may contain characters indicating quantities or the number of articles accompanying a ticket. The type characters on the type-bars 29, 30 30 and 31 are in duplicate, one set at one end and the other at the other end, to enable the machine to print along two rows of tickets. The type-bars 29 provide means for consecutively numbering the coupons, and the type-bars 30 and 31 for printing the additional 35 data on the coupons, and all of any group are arranged to print information occupying a space well within the margin of a coupon. Similar spaced groups of type-bars, bearing type characters, are employed 40 for printing upon as many coupons as are included in the ticket, and obviously the machine can be constructed to embody any desired number of groups of type-bars.

The type-bars are provided near their 45 upper edges with shouldered portions 32 that rest upon the plates 23, and below said shouldered portions elongated slots 33 are formed in the type-bars through which extends a pin 34 which acts to retain all of 50 the type-bars in place, and in mesh with pinions, as will be described hereinafter. Said pin 34 extends through one end member 20^a of the frame 20, and has a head or knob 34^a on its end by means of which the 55 pin may be inserted through the slots of the type-bars and withdrawn therefrom. It will be understood that said pin 34 also extends through alined holes in the plates 23.

Inasmuch as the data which is printed by 60 the type characters of the type-bars 30 and 31 varies and may be changed from time to time in the establishment where the machine is used, the type characters for said type-bars 30 and 31 are preferably made removable, and I have shown said type-bars 30

and 31 as formed with notches 35 in their upper edges (see Fig. 9) in which are removably secured type 36 (see Figs. 12 and 13) containing type characters on their upper faces. Said type-bars 30 and 31 and 70 type 36 are formed with shoulders 32 and 38 adapted to rest upon the plates 23, and the type 36 are formed with upwardly-extending notches 39^a in their lower ends to form 75 forked portions that straddle the webs of the type-bars 30 and 31 (see Figs. 9, 10 and 12).

Means for setting the corresponding type-bars in the several groups of the type-bars are provided and, as illustrated, typesetting 80 bars 39, 40 and 41 are provided at one end of the machine, which are also slidably mounted on plates 23 and have elongated slots 33 for the reception of the pin 34, whereby they may be locked in place. The 85 lower edges of the typesetting bars are provided with rack teeth 42 which mesh with pinions 43 fast upon shafts 44 that are rotatably mounted in the plates 23 and have other pinions 45 thereon that mesh with 90 rack teeth 46 formed on the lower edges of the type-bars 29, 30 and 31. It will be understood that there is one typesetting bar for the corresponding type-bars in the several groups, and that a shaft which is moved 95 by any typesetting bar is provided with pinions meshing only with rack teeth of corresponding type-bars in each group, so that when any typesetting bar is moved to set the type-bars controlled thereby, one type-bar in each group will be moved thereby. Fig. 7 illustrates the connection between the typesetting bar 39 and corresponding type-bars 30 of two groups. When the shaft 44 is turned by moving the typesetting bar 39, 100 all of the pinions 45 on said shaft are correspondingly rotated and the type-bars 30 are correspondingly moved to bring the desired type characters thereof into printing position. Likewise, all of the other corresponding 105 type-bars may be adjusted by manipulating the typesetting bars therefor. Fig. 2 shows the arrangement of the typesetting bars, the setting shafts and pinions. The upper faces of the typesetting bars 39, 40 110 and 41 are provided with figures or characters representing the type characters of the type-bars 29, 30 and 31, and these figures on the typesetting bars are visible through holes 47 formed in a cover plate 48 secured 115 or otherwise fastened to the frame 20. Spring detents 49 (see Fig. 4) secured to the cover plate 48 engage with notches in the upper edges of the typesetting bars and hold them in any position of adjustment. 120

A cover plate 50 is provided over the type-bars, which cover plate is screwed or otherwise fastened to the frame 20 and has lengthwise-extending slots 51 arranged at the printing position of the type characters, 130

which exposes two rows of type characters that print on the coupons of the ticket whenever the platen is depressed. A guide strip 52 is adjustably secured to the cover 50 against which the coupon ticket is placed when it is to be printed on.

The platen 53 (see Figs. 1, 5 and 6) is in the form of an openwork rectangular frame 53^a rockingly carried by a rod 54 which is 10 rotatively supported in two arms 55, which are pivotally mounted on ears 56 by a rod 57 which extends through holes in the ends of the arms 55 and ears 56. Coiled compression springs 58 secured in the frame 20 15 and bearing against the under sides of the arms 55 act to yieldingly hold the arms 55 and platen in raised position as seen in Figs. 5 and 6. The mechanism for bringing the platen down upon the coupon ticket to obtain 20 the impression from the type characters may comprise a handle 62 and crank arms 59 fast upon the shaft 54 and having rollers 60 that engage with the under side of brackets 61, which are secured to and extend 25 up from two plates 23 of the type-bar supporting frame. It will be observed that by swinging the handle 62 from the position shown in Fig. 5 to that shown in Fig. 3, the crank arm 59 with its roller 60 will be correspondingly moved; and that by 30 reason of the engagement of the roller 60 with the under side of the bracket 61 the platen will be moved downward from the position shown in Fig. 5 to that shown in Fig. 3, thereby bringing the effective or 35 working surfaces of the platen into pressing contact with the coupon ticket. When the handle 62 is released, the springs 58 act to return the platen to its inoperative position.

To the platen frame 53^a are secured two 40 rubber, tubular, impression-making members 70 (see Fig. 15) that are arranged upon the under side of the platen frame in position to engage the ticket along places immediately 45 above the type characters exposed through the slots 51 and occupying the printing positions. Within each rubber tube 70 is a rectangular rod or bar 71 to which is secured two threaded pins 72 that extend up 50 through slots 73 in the platen frame 53^a and have nuts 74 upon their ends which may be clamped against the upper faces of the platen frame to securely fasten the bars 71 with the rubber tubes 70 in position to effect 55 the printing whenever the platen is depressed. It is evident that the rubber tubes and bars may be adjusted transversely of the platen frame so as to bring them into accurate printing position with respect to the type characters that have been set into printing position. The type characters below 60 the slots 51 in the cover 50 are the ones occupying the printing position.

An inked ribbon 75 (see Fig. 6) is provided 65 between the cover 50 and type-bars

29, 30 and 31, which inked ribbon is carried by rollers 76 and 77—one of which (76) is rotatively mounted on the brackets 61, and the other of which (77) is rotatively mounted in a roll-carrying frame 78 which may 70 comprise a flat bar bent to form two transverse bent portions 79, which are pivotally connected with the frame 20 of the machine by screws 80. Upon the ends of the roller 77 are knurled heads by which the roller 75 may be turned to wind the ribbon up from the roller 76 to the roller 77 as it becomes worn.

A register 82 may be attached to the frame of the machine and connected to the 80 platen for recording the number of times that the platen is depressed to make an impression.

In use, the typesetting bars are adjusted to bring the desired type characters into 85 printing position. A coupon ticket is placed upon the cover 50 with one edge in contact with the guide 52, and the handle 62 is swung over from the position seen in Fig. 5 to that seen in Fig. 3, thereby bringing 90 the rubber impression-making tubes upon the ticket and pressing the same down, causing the type characters, which are in printing position, to make impressions on the coupons through the interposed inked ribbon. When the handle 62 is released, the 95 platen assumes its normal or inoperative position.

In case it is desired to change the removable type characters, the cover 50 is removed from the frame and the roller-carrying frame 78 with the roller and ribbon is swung up to the position shown in dotted lines in Fig. 6. The locking pin 34 is then withdrawn and any or all of the type-bars 105 may be removed from their supporting frame by lifting them up and pulling them out of the spaces between the guide plates 23. After the type have been rearranged or changed as desired, the type-bars may be 110 replaced between the guide plates 23, the roller frame 78 may be swung down into place, and the cover 50 replaced on the frame.

The parts are simple in construction and 115 are strong, rigid and capable of long and continued usage. The frame make-up of the guide plates and associated parts forms a rigid backing for the type-bars which rest on the plates. The rods 71 form reinforcements or backing bars for the rubber impression members, thus insuring the making of clear impressions along the entire ticket, and the adjustable roller-carrying frame 78 provides convenient means for raising the 120 ink ribbon to gain access to the type-bars 125 therebelow.

More or less variation of the exact details of construction is possible without departing from the spirit of this invention; I de- 130

sire, therefore, not to limit myself to the exact form of the construction shown and described, but intend, in the following claims, to point out all of the invention disclosed herein.

I claim as new and desire to secure by Letters Patent:

1. In a coupon ticket printing machine, the combination of spaced, parallel plates, 10 slideable type-bars having web portions extending between said plates and shouldered portions resting on the upper edges of said plates, said type-bars having type characters on their upper faces, and being arranged in spaced groups.
2. In a coupon ticket printing machine, the combination of spaced, parallel plates, type-bars having web portions extending between said plates and shouldered portions 20 resting on the upper edges of said plates, there being notches formed in the upper edges of said type-bars, and type having type characters on their upper faces, said type being removably held in said notches, 25 and having shouldered portions resting on said plates and forked portions extending between the plates and straddling the webs of the type-bars.
3. In a coupon ticket printing machine, 30 a type-bar having notches in its upper edge for receiving removable type, and adjacent shoulders arranged to rest upon suitable supports and rack teeth on its lower edge, arranged to mesh with the pinion of the setting mechanism.
4. In a coupon ticket printing machine, 35 the combination of a plurality of spaced parallel plates, type-bars slidably supported thereon, and formed with lengthwise-extending slots, and with rack teeth on their lower edges, type-bar-setting pinions meshing with said rack teeth and a locking pin extending through said slots and through 40 holes in said plates for holding said rack teeth and pinions in mesh.
5. In a coupon ticket printing machine, 45 the combination of a plurality of spaced, parallel plates, type-bars slidably supported thereon, and formed with lengthwise-extending slots, and with rack teeth on their lower edges, type-bar-setting pinions meshing with said rack teeth and a removable locking pin extending through said slots and through 50 holes in said plates for holding said rack teeth and pinions in mesh.
6. In a coupon ticket printing machine, a main frame, a type-bar supporting frame mounted therein, type-bars adjustably mounted in said type-bar supporting frame, 60 platen carrying arms, a platen pivotally mounted on said arms between its side edges whereby said platen is free to rock on its pivot, and means for pressing said platen indirectly upon the type-bars.
7. In a coupon ticket printing machine,

a main frame, a type-bar supporting frame mounted therein, type-bars adjustably mounted in said type-bar supporting frame, upwardly spring-pressed platen-carrying arms, pivotally supported on said main frame, a platen, stationarily-supported brackets adjacent the ends of said platen, a rock shaft pivotally connecting said platen with said arms, cranks on said rock shaft co-operating with said brackets to depress 75 the platen when rocked in one direction, and a handle on said rock shaft for actuating the same.

8. In a coupon ticket printing machine, a platen frame, a rubber impression-making 80 tube, a bar filling said tube and secured to said platen frame.

9. In a coupon ticket printing machine, a platen frame, a rubber impression-making tube, a bar filling said tube, and means for 85 adjustably mounting said tube and bar on said platen frame.

10. In a coupon ticket printing machine, a platen frame having transverse slots 90 therein, a rubber impression-making tube, a bar filling said tube, threaded pins secured to said bar and extending through the slots in said bar, and nuts threaded on said pins for adjustably clamping said tube and bar upon said platen frame.

11. In a coupon ticket printing machine, a plurality of removable, spaced, parallel type-bars, an inked ribbon overlying said type-bars, rollers upon which said ribbon is wound, one of which is movably supported, 100 whereby it and part of the ribbon carried thereby may be raised to obtain access to said type-bars, for the purpose set forth.

12. In a coupon ticket printing machine, a plurality of removable, spaced, parallel 105 type-bars, an inked ribbon overlying said type-bars, rollers upon which said ribbon is wound, and a pivotally-supported roller-carrying frame in which one of said rollers is mounted, said frame and therewith the 110 roller and part of the ribbon carried thereby being capable of being raised to expose the type-bars, for the purpose set forth.

13. In a coupon ticket printing machine, the combination of a supporting frame, a 115 plurality of type-bars slidably mounted on said frame, each type-bar forming one member of a group of type-bars and having rack teeth on its lower side, a typesetting bar slidably mounted on said frame and having 120 rack teeth on its lower side, a shaft journaled in said frame, and pinions fast on said shaft and meshing with the rack teeth of the type-bars and typesetting bars.

14. In a coupon ticket printing machine, 125 the combination of a supporting frame, a plurality of type-bars slidably mounted on said frame, each type-bar forming one member of a group of type-bars and having rack teeth on its lower side, a typesetting bar 130

slidably mounted on said frame and having rack teeth on its lower side, a shaft journaled in said frame, pinions fast on said shaft and meshing with the rack teeth of 5 the type-bars and typesetting bars, and a locking pin extending through slots in said type-bars and typesetting bars.

15. In a coupon ticket printing machine, a type bar having notches in its upper edge,

and type forked on their lower ends, the 10 forks straddling the type bar, and being removably carried thereby.

16. In a coupon ticket printing machine, a type bar having notches in its upper edge, and forked type straddling said type bar, 15 said type having also shoulders on their sides arranged to rest on suitable supports.

MORRIS J. HOFFMAN.
